US00D956728S

(12) **United States Design Patent** (10) **Patent No.:** **US D956,728 S**
(45) **Date of Patent:** **** Jul. 5, 2022**

(54) **DATA TRANSMITTING AND RECEIVING DEVICE**

(71) Applicant: **Panasonic Intellectual Property Management Co., Ltd.**, Osaka (JP)

(72) Inventors: **Shinichi Takiguchi**, Tokyo (JP);
Takashi Koyama, Kanagawa (JP)

(73) Assignee: **Panasonic Intellectual Property Management Co., Ltd.**, Osaka (JP)

(**) Term: **15 Years**

(21) Appl. No.: **29/743,278**

(22) Filed: **Jul. 21, 2020**

(30) **Foreign Application Priority Data**

Jan. 29, 2020 (JP) ..... 2020-001502 D

(51) **LOC (13) Cl.** **14-03**

(52) **U.S. Cl.**

USPC **D14/230**; D14/242

(57) **CLAIM**

We claim the ornamental design for a data transmitting and receiving device, as shown and described.

DESCRIPTION

FIG. 1 is a front perspective view of a data transmitting and receiving device of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines in the drawings represent portions of the data transmitting and receiving device that form no part of the claimed design.

1 Claim, 8 Drawing Sheets
